(57) **CLAIM**

The ornamental designs for a percussion mallet, substantially as shown and described.

DESCRIPTION

FIG. 1 is a perspective view of a percussion mallet in accordance with the present invention;

FIG. 2 is a right side elevational view of the percussion mallet shown in FIG. 1;

FIG. 3 is a left side elevational view of the percussion mallet shown in FIG. 1;

FIG. 4 is a bottom plan view of the percussion mallet shown in FIG. 1; and,

FIG. 5 is a top plan view of the percussion mallet shown in FIG. 1.

The broken lines in FIGS. 4 and 5 represent the portions of the design, which form no part of the claim.
